UNITED STATES PATENT OFFICE.

OLIVER G. LAW, OF DAYTON, OHIO.

DOCUMENT-FILING ENVELOP.

No. 923,539.

Specification of Letters Patent.

Patented June 1, 1909.

Application filed April 8, 1908. Serial No. 425,802.

To all whom it may concern:

Be it known that I, OLIVER G. LAW, citizen of the United States, residing at Dayton, in the county of Montgomery and State of Ohio, have invented certain new and useful Improvements in Document-Filing Envelops; and I do declare the following to be a full, clear, and exact description of the invention, such as will enable others skilled in the art to which it appertains to make and use the same, reference being had to the accompanying drawings; and to the letters of reference marked thereon, which form a part of this specification.

This invention relates to improvements in document filing envelopes, such as are used for filing papers in probate, common pleas and other courts. Owing to the great number of such filing envelopes so used, it is the custom on account of the economy in space, to arrange such envelopes upright, one in the rear of the other in assemblages of from one to two dozen, and to compress them together by a clamp in the rear. This renders it difficult to select an envelope from the assemblage without releasing the clamp or removing a number of envelopes in order to enable the title or number of the case inscribed thereon to be read in selecting the envelope to be removed. In order to remove this difficulty and to enable a selection of any desired envelope without being put to the trouble of releasing the clamp or removing those envelopes in front, is the primary object of the present invention. This is accomplished by extending the front of each envelope a suitable distance above the top of the envelope proper to provide necessary space for the notation of the number of the case or any other data indicating the papers filed in each particular envelope. Owing to the great amount of handling that these envelopes are subjected to, it is important that they be so constructed as to not tear at the mouth of the envelope, the place most liable to give way. It is therefore another object of the invention to reinforce the sides of the envelope adjacent to the mouth to give such parts suitable tenacity and wearing quality.

Preceding a detail description of the invention, reference is made to the accompanying drawings, of which—

Figure 1, is a view of an assemblage of filing envelopes in perspective, after the manner of arranging them in probate court offices and elsewhere. Fig. 2, is a vertical lon-

gitudinal section through one of such envelopes on the line *c c* of Fig. 1. Fig. 3, is a cross section of an envelope just below the mouth on the line *b b* of Fig. 2. Fig. 4, is a detail sectional view of one side of the envelope on the line *a a* of Fig. 2.

In a detail description of the invention, similar reference characters indicate corresponding parts.

The assemblage of filing envelopes shown in Fig. 1, are each identical in construction and are there shown one in the rear of the other as is customary in using them in probate courts and other places where their use is demanded. Each of such envelopes consists of a front A and a rear side B which are united at their longitudinal and bottom edges by inwardly-breaking folds C, otherwise termed accordion plaits. The front of such filing envelopes is utilized for various engrossing data relating more or less to the contents of the papers or files contained therein. The accordion plaits or side folds provide well-known means for enabling the envelope to enlarge or expand according to the bulk of the contents thereof.

A novel feature of the present invention lies in extending the front A of the envelope above the mouth of the envelope as indicated by D for two purposes; first to enable such extended portion of each envelope to contain a suitable index to the contents thereof which may be seen without necessitating the release of the clamp which holds them compact, or the removal of the envelope in front of the one to be removed. In the present instance, "No." is inscribed on this extended portion of each envelope with a line extending therefrom upon which the number of the case to which the papers contained in the envelope relate, may be placed, or any other data which may be an index to the contents of the envelope.

It will be seen from Fig. 1, that when a number of these envelopes are placed one in the rear of the other, these extended portions D may be seen without it being necessary to remove the envelopes in front of it or releasing the clamp. Another advantage of this extended portion D of the envelope is that it provides a convenient finger-hold by which the envelope may be conveniently withdrawn by the hand. The inside of the envelope at the mouth is reinforced by the application of strips of muslin E in order to strengthen the same. In the construction of the side folds

- of the envelop, said folds are extended up beyond the mouth of the envelop and are folded over on the inside of the envelop as at G and are adhered to the inner sides of the folds at such points. This adds double strength to the envelops at these points which are called upon to withstand the greater portion of the strain due to the placing of the contents in the envelops and their removal therefrom.
- 10 The front and rear sides of the envelop are carried around the edges as at A' and B' and are there inclosed on the outer sides by the strips C, the upper ends of which are carried over in the form of the reinforcing portions 15 G, so that the parts A' and B' coöperate with the strips C on each side of the envelop and doubly increase the strength of the folds.

I claim:

- 20 The herein-described document filing envelop comprising front and rear sides united at their longitudinal edges by inwardly-breaking folds, the front of the envelop being

extended above the mouth thereof to provide a space for an index to the contents of the envelop, and to provide a hand-hold for the 25 withdrawal of the envelop from its filing position, the inwardly-breaking folds uniting the front and rear sides, being constructed by extending the longitudinal edges of said front and rear sides inwardly and reinforcing them 30 on their outer sides by longitudinal strips which are carried upwardly and turned over at their upper ends into the mouth of the envelop and there caused to adhere to the inner sides of the inturned longitudinal edges of the 35 front and rear sides of the envelop, substantially as shown and described.

In testimony whereof I affix my signature, in presence of two witnesses.

OLIVER G. LAW.
